UNITED STATES PATENT OFFICE.

GROVER CLEVELAND WELTER, OF ROSWELL, NEW MEXICO.

BOW.

1,418,218.

Specification of Letters Patent. Patented May 30, 1922.

Application filed January 25, 1921. Serial No. 439,816.

To all whom it may concern:

Be it known that I, GROVER CLEVELAND WELTER, a citizen of the United States, and a resident of Roswell, in the county of 5 Chaves and State of New Mexico, have invented a new and Improved Bow, of which the following is a full, clear, and exact description.

In connection with tops and more particularly that type of top serving as a covering for vehicles of the automotive type, it is well appreciated that two paramount defects have been experienced.

The first of these defects is to be found in 10 that the bows serving to support the top when it is in its raised position, are usually constructed of wood. This material is the most desirable in that the seam may be sheathed so as to conform to the various 15 curves desired, at the same time giving those necessary qualifications of strength and lightness. However, due to the vibrations incident to the operation of the vehicle and the action of air currents thereon, a constant 20 movement of the top with respect to the supporting bows comes constantly into being. Minute particles or splinters become separated from the edges of the bows supporting the top, due to this movement, and thus a rough edge is provided which at all 25 times bears against the top, quickly resulting in deterioration of the same in that a fabric provided as a covering quickly becomes worn through at those points which 30 contact with the bows.

A second defect experienced in connection 35 with bows of this type is the wearing action exerted by the same upon the bracing straps lying adjacent the under side of the top 40 covering. A subsidiary defect experienced in connection with the last enumerated objection is to be found in that straps are in some instances secured to the body of the bows, this being effected by means of tacks 45 or similar retaining elements. Due to the vibration of the parts and shrinkage, the openings through the straps provided for the passage of the securing elements quickly become enlarged, resulting in an unsightly 50 appearance on the part of the strap aside from the general weakening of the same.

Having these defects in mind, I have now 55 constructed a bow more particularly intended for use in connection with the supporting of the covering for vehicles, which bow shall be constructed in such a manner that

no danger of the fabric becoming unduly worn adjacent its points of contact with the bow exists.

A further object of my invention is the 60 construction of a device of this nature, which shall provide certain novel retaining means for the straps, by means of which they will be held without danger of the same becoming worn or torn. Reference is had to the 65 attached sheet of drawings which illustrate one practical embodiment of my invention, and in which—

Figure 1 is a sectional side view taken through the top and its supporting bows, 70 which are shown as applied to a vehicle of the type specified.

Figure 2 is an enlarged plan view of one of the bows, and

Figure 3 is an enlarged sectional side view 75 taken on lines 3—3 of Figure 2.

For convenience of illustration, I have shown my invention as applied to what is known as a five-bow type, in which front and rearmost bows 5 and 6 respectively, 80 may be constructed in any conventional manner if this is desired, as the fabric forming the top 7 is fixed to these bows, the intermediate bows, i. e., those bows serving to support the fabric 7 by merely having the 85 same rest upon them, being constructed in accordance with my improved design.

Referring now more particularly to Figures 2 and 3 which illustrate a bow constructed in accordance with my invention, 90 it will be seen that the bow 8 may be of any desirable material and constructed in any conventional manner, the curved and center portions of said bow being conveniently wrapped as at 9. However, contrary to the 95 conventional construction, a covering of metal is associated with the bow 8 and extends preferably intermediate its curved portions. This covering 10 may be of any desired metal adaptable for this purpose as 100 long as the exterior face of the same presents a smooth surface. As has been illustrated in Figures 2 and 3, tacks or other suitable securing members 11 may be utilized for retaining the metal covering 10 in 105 applied position.

Now with a view of providing securing means for the straps 12 and retaining the same in such a manner that no damage to these members will result, openings are provided through the cover at a point adjacent that at which the same is bent downwardly 110

to conform to the side walls of the bow adjacent their point of connection with the upper surface, thus providing what might be termed a channel through which one of the straps 12 may pass, the same occupying a position intermediate the upper face of the bow 8 and the inner face of the covering 10.

This construction, as will readily be appreciated, will serve by virtue of the frictional engagement existent between the elements enumerated, to prevent any relative movement on the part of the straps 12 with respect to the bows 8, although the former are held in such a manner that no danger of injury to the same may result.

Thus, I have provided a bow more particularly applicable for use in connection with supporting the fabric of an automotive vehicle top, but which is not necessarily limited to this connection and by means of

which the top will be supported in such a manner that no undue wear may come into being between the same and the bow adjacent their points of contact, it being further noted that the straps are held in the most desirable manner.

Obviously, numerous modifications of structure might readily be resorted to without in the least departing from the scope of my claim, which reads:

A bow including a body portion, a layer of metal presenting a smooth outer face encircling said body portion adjacent its points of contact with the top covering to be supported by said bow, said metal being formed with openings, the top supporting straps being adapted to pass through said openings and being clamped in this position by means of the body of said metal.

GROVER CLEVELAND WELTER.
